UNITED STATES PATENT OFFICE

HENRY KOCH, OF JAMAICA, NEW YORK, ASSIGNOR TO DICTOGRAPH PRODUCTS CO., INC., OF NEW YORK, N. Y., A CORPORATION OF DELAWARE

ACOUSTIC DEVICE

Application filed October 3, 1931. Serial No. 566,678.

This invention relates to acoustic devices and more particularly to ear-phone receivers, and has for a general object the provision of such a device which can be comfortably retained in the ear of the user without the use of an external support, which is adjustable to fit a variety of types and sizes of ears and can be manipulated to fit either the right or the left ear of the user.

10 A more specific object of the invention is the provision of such a device having an adjustable member which can be readily manipulated in a manner such that the receiver will efficiently and comfortably fit and be securely retained in a plurality of different sizes and types of conchas of both right and left ears.

15 A further object of the invention is the provision of such a device having a readily deformable arm terminating in a portion adapted to engage the fleshy convolutions of the concha, the arm being angularly adjustable to adapt the receiver to either the right or the left concha of a plurality of 20 sizes of ears and axially adjustable to insure a comfortable fit in a plurality of types of ears.

25 Other objects of the invention will in part be obvious and will in part appear herein-after.

30 The invention accordingly comprises the features of construction, combination of elements, and arrangement of parts, which will be exemplified in the construction hereinafter set forth and the scope of the application of which will be indicated in the claims.

35 For a fuller understanding of the nature and objects of the invention reference should be had to the following detailed description 40 taken in connection with the accompanying drawing, in which:

Fig. 1 is a side elevation of the ear-phone receiver of the present invention.

Fig. 2 is a similar view of the case member 45 in which the receiver is inclosed.

Fig. 3 is a side view of a portion of the ear piece to be mounted on the case member depicted in Fig. 2, with parts in section.

Fig. 4 is an enlarged elevational view of 50 the collar constituting the connection between

the member depicted in Fig. 3 and the case member depicted in Fig. 2, with parts in section.

Fig. 5 is a plan view of the adjustable member constituting part of the ear piece. 55

Fig. 6 is a plan view of the ear-phone receiver depicted in Fig. 1, with a plurality of positions of the adjustable member shown in dotted lines, and

Fig. 7 is a diagrammatic illustration of the 60 acoustic device of the present invention mounted on the left ear of a user.

Prior to the present invention, ear-phone receivers adapted for use as auricular devices for the aid of persons afflicted with 65 defective hearing have been designed in a manner such that they will fit only the right or the left concha, but not both, of a limited number of different types and sizes of ears. This is due to the fact that such devices are 70 usually integrally formed or securely mounted with an offset projecting portion adapted to fit the external auditory meatus and a member designed to conform the general outline of the upper portion of the concha such that the 75 latter will engage in the fleshy convolutions of the concha and retain the device in position. Thus such devices designed for the right ear will not fit the left ear and since most ears differ materially in size and shape, 80 an ear piece that may admirably fit one ear can not be comfortably used in the other ear or by any great number of persons.

In accordance with the present invention, 85 an ear-phone receiver of this type is provided which substantially eliminates the difficulties of the devices of the prior art and which is readily adjustable to comfortably fit either the right or the left concha of a plurality of types and sizes of ears. 90

Referring to the drawing, like numerals refer to like parts throughout. In Fig. 1 is shown an elevational view of the ear-phone receiver of the present invention, consisting of a receiver inclosed in a case member 10 95 on which is mounted an ear piece 11 comprising a projecting portion 12 adapted to fit the auditory external meatus and an adjustable member 13 adapted to engage the fleshy convolutions of the concha, a stud 14 is centrally 100

mounted on this case member as shown in Fig. 2 and is provided with an auditory duct communicating with the inside of the case member 10. This stud is provided with an 5 enlargement 15 which is preferably formed by an annular thickening of the stud as shown, but which may be provided by mounting an additional member on the stud to extend either entirely or partially of the 10 circumference of the stud, or by a slot or groove formed in the external surface of the stud.

The projecting portion 12 is preferably molded integral with the base member 16 from any suitable material, such as, for example, bakelite or hard rubber, in a position such as to be offset from the axis of the latter as is shown in Fig. 3. This base member is provided with a recess 17 to receive a collar 18 which is secured to the base member by 15 any suitable means, preferably by molding the base member about the collar 18. The base member 16 and the projecting portion 12 are provided with an auditory duct 19 which communicates with the recess 17 such 20 that it will terminate inside the collar 18.

The collar 18 is preferably made from any suitable metal and provided with an external flange 20 for a purpose to be explained later. An annular groove 21 is formed in 25 the inner surface of the collar and a spring ring 22 is disposed within this groove to engage beyond the enlargement 15 on the stud 14. The collar 18 is of such a dimension that it will receive the stud 14 with the spring 30 ring 22 engaging beyond the enlargement 15 in such a manner as to allow relative rotation of the collar with respect to the stud with sufficient frictional engagement to maintain the ear piece in any desired position 35 relative to the casing member 10.

The adjustable member 13 comprises a metallic ring 23 preferably provided with an offset arm 24, preferably formed of readily deformable metal, terminating in a button 40 25 to engage the fleshy convolutions of the concha. The ring 23 is additionally provided with spring fingers 26, to encircle collar 18 above its flange 20 so that the adjustable member 13 will be rotatably mounted on the 45 collar 18 and on base member 16 with sufficient frictional engagement to maintain the former 50 in any desired position relative to the latter.

In use, the adjustable member 13 is manipulated to a suitable position, such as, for example, that depicted at 27 in Fig. 6 which 55 may be indicated on the base member 16 by any suitable mark. In such a position the ear piece is adapted to fit the concha of the right ear, the exact position shown being 60 arbitrarily chosen since the ear piece is adapted to fit a plurality of sizes of ears.

To adapt the ear piece to an ear which is 65 much larger than that which will comfortably receive the ear piece with the adjustable member in the position shown at 27, the ad-

justable member 13 is rotated further to the right, such as, for example, to the dotted position indicated at 27', thus increasing the distance between the button 25 and the projecting portion 12. For an ear having a 70 smaller concha, the adjustable member 13 is rotated further to the left to shorten the distance between the button 25 and the projecting portion 12.

To adapt the ear piece to a left ear, the 75 adjustable member 13 is rotated to the right to a position indicated in dotted lines at 28, which may be properly identified on the base member by a suitable mark, the member 13 being adjustable for the size of the concha 80 as in the case explained above in connection with the right ear, the distance between the button 25 and the projecting portion 12 being increased by rotating the adjustable member 13 to any desired position such as 85 that indicated by the dotted lines at 28'.

Axial adjustment of the arm 24 relative to the portion 12 may be made by bending the former to alter the offset distance of the button 25 relative to the plane of the ring 23 90 to obtain the desired adjustment. The ears of different persons not only differ in size in lateral contour but also in axial dimensions, that is, in the axial distance between the opening of the external auditory meatus or lower portion of the concha and the innermost surface of the upper portion of the concha. Such variations are readily accommodated by the bending of the arm 24 in 95 the manner set forth above. This arm may 100 also be bent to alter the distance between the button 25 and the axis of the ring 23 when it is desired to adapt the ear phone to an unusually large or small ear which can 105 not be fit by an angular adjustment of the member 13.

The ear-phone receiver is mounted in the ear of the user in the manner shown in Fig. 7 with the projecting portion 12 fitting into the external auditory meatus and the button 110 25 of the adjustable member 13 engaging the fleshy convolutions of the upper portion 29 of the concha. When so mounted the ear piece comfortably fits the convolutions of the 115 ear with the adjustable member 13 serving to retain it in position.

The ear piece 11 is preferably made angularly adjustable with respect to the casing member 10 so that the electrical conductors will hang down from the lower side of the 120 casing member when the latter is in position in either the right or the left ear.

It is to be understood that the present invention can be practiced without departing from the scope thereof by using means other than those shown for mounting the ear piece 11 on the casing member 10 and for mounting the adjustable member 13 in the assembly so long as the adjustable features of the member 13 and the ear piece 11 are retained, and that 125 130

the following claims are intended to cover all of the generic and specific features of the invention herein described.

Since certain changes may be made in the 5 above construction and different embodiments of the invention could be made without departing from the scope thereof, it is intended that all matter contained in the above description or shown in the accompanying 10 drawing shall be interpreted as illustrative and not in a limiting sense.

Having described my invention, what I claim as new and desire to secure by Letters Patent, is:

15 1. In an ear-phone receiver, an adjustable ear piece comprising a member having a base provided with a projecting portion adapted to fit the external auditory meatus the axis of which is offset with respect to the axis of said 20 base and a member mounted concentric with said base, said last mentioned member being angularly adjustable with respect to said base and having an offset arm adapted to fit into the fleshly convolutions of the concha.

25 2. In an ear-phone receiver, an adjustable ear piece comprising a member having a circular base provided on one side with an offset projecting portion adapted to fit the external auditory meatus and on the other 30 side with a central projecting collar, said base and projecting portion being provided with an auditory duct terminating inside said collar, a ring rotatably mounted on said collar, said ring having a member adapted to fit into 35 the fleshly convolutions of the concha.

3. An ear-phone receiver comprising a case member inclosing a receiver, a stud projecting from the face of said case member, said stud being provided with an auditory duct, 40 an ear piece member mounted on said stud, said last mentioned member comprising a base having on one side a projecting portion adapted to fit the external auditory meatus and means on the other side to engage said 45 stud, said base and projecting portion being provided with an auditory duct communicating with the auditory duct in said stud, and means rotatably mounted on one of said members adapted to engage the fleshly convolutions 50 of the concha to hold said ear-phone receiver in position.

4. An ear-phone receiver, comprising a case member inclosing a receiver, a central stud projecting from the face of said case 55 member, said stud being provided with an auditory duct, an ear piece member rotatably mounted on said stud, said last mentioned member comprising a base having on one side an offset projecting portion adapted to fit 60 the external auditory meatus, and means on the other side adapted to engage said stud, said base and projecting portion being provided with an auditory duct communicating with the auditory duct in said stud, means 65 rotatably mounted between said case member

and said ear piece member, said last mentioned means having a projecting member adapted to engage the fleshy convolutions of the concha to hold the ear-phone receiver in position.

5. An ear-phone receiver comprising a case member inclosing a receiver, a central hollow stud projecting from the face of said case member, an external enlargement on said stud, a collar adapted to fit over said stud, means on said collar to engage beyond said enlargement, an ear piece base secured to said collar to be rotatably mounted on said case member, a projecting portion mounted on said base, said portion being offset with respect to the axis of said collar and adapted to fit the external auditory meatus, said portion and said base being provided with an auditory duct terminating inside said collar, and a ring rotatably mounted on said collar, 85 said ring having a projecting member adapted to engage the fleshy convolutions of the concha to hold said ear-phone receiver in position.

6. An ear-phone receiver comprising a casing inclosing a receiver, an ear piece member having a base mounted concentric with said casing and a projecting portion adapted to fit the external auditory meatus the axis of which is offset with respect to the axis of the base, and a member mounted concentric with said casing and having a laterally extending portion adapted to fit into the fleshly convolutions of the concha, one of said members being angularly adjustable with respect to 95 said casing.

In testimony whereof I affix my signature.
HENRY KOCH.
